J. P. BALDWIN

SADDLE HORN

Filed June 9, 1927

Inventor

J. P. Baldwin,

By *John Murphy Jr.* Attorney

UNITED STATES PATENT OFFICE.

JOSEPH P. BALDWIN, OF KINGSVILLE, TEXAS, ASSIGNOR TO THE KINGSVILLE LUMBER COMPANY, OF KINGSVILLE, TEXAS.

SADDLE HORN.

Application filed June 9, 1927. Serial No. 197,600.

This invention relates to a saddle horn, and has for one of its objects to provide a device of this character with a base which shall be non-breakable and which shall be 5 adapted to embrace and be secured to the swell of a saddle-tree in a manner to prevent the horn from being detached from the swell by the severest strain to which the horn is likely to be subjected.

10 A further object of the invention is to provide a horn of the character stated wherein in the base and the attaching means therefor shall be adapted to prevent the separation of the lateral halves or sections of the swell.

15 With the foregoing and other objects in view, the nature of which will become apparent as the description proceeds, the invention consists of the construction, combination and arrangement of parts hereinafter 20 fully described and claimed, and illustrated in the accompanying drawing, wherein:

Figure 1 is a view partly in side elevation and partly in vertical section of the swell of a saddle-tree equipped with a horn embodying my invention,

25 Figure 2 is a view in front elevation of the swell and horn,

Figure 3 is a view in rear elevation of the swell and horn, and

30 Figure 4 is a detail sectional view taken on the vertical plane indicated by the line 4-4 of Figure 1.

Referring in detail to the drawing, 1 designates the swell of a saddle-tree which is 35 made of wood. The swell 1 is provided in its top side with a forwardly and rearwardly extending recess 2, and is formed of two lateral halves or sections secured together by a dovetail joint, as shown at 3. The horn

40 4 and its base 5 are made of metal and formed integrally. The base 5 which seats in the recess 2, extends forwardly and laterally beyond the horn 4 and is provided at its front end with a hook 6 which is as wide as the base and extends downwardly and rearwardly therefrom. The bite portion of the hook 6 snugly embraces the front edge of the swell 1 and the bill portion thereof contacts with the under side of the swell.

45 50 The hook 6 extends laterally beyond the joint 3 of the sections of the swell 1, and is

secured in place by screws 7 which enter the under side of the swell at opposite sides of the joint. The base 5 is provided at its rear end with downwardly and laterally extending prongs 8 which seat against the rear edge of the swell 1 at opposite sides of the joint 3, and are secured in place by screws 9 which enter said edge of the swell at opposite sides of the joint.

The base 5 and its hook 6 are of solid construction throughout their entire lengths and width. Due to this construction thereof, the base 5 will not break under the severest strain to which it may be subjected. The solid construction of the hook 6 and the manner in which it embraces the front edge of the swell 1 and contacts with the under side of the swell, together with the prongs 8, prevent the base 5 from becoming detached 70 from the swell under the severest strain to which the base may be subjected. As the hook 6 extends laterally beyond the joint 3 and as the attaching screws 7 therefor enter the swell at opposite sides of the joint, the lateral halves or sections of the swell are held against separation under the strain to which the swell would be subjected in the event that the horse should fall with the saddle under him.

It should be understood that the drawing is merely illustrative and does not pretend to give exact proportions. Furthermore, the said drawing is illustrative of a preferred construction, it being my expectation that 85 various changes and modifications may be made without departing from the spirit and scope of my invention.

What is claimed is:—

1. In combination, the swell of a saddle-tree, and a horn having a base seated on and secured to the swell and provided with a hook embracing the front edge of the swell.

2. In combination, the swell of a saddle-tree, and a horn having a base seating on and secured to the swell and provided with a hook embracing the front edge of the swell and contacting with the under side of the swell.

In testimony whereof I affix my signature.

JOSEPH P. BALDWIN.
